United States Patent Office.

MAHLON HAMLIN, OF CATAWISSA, ASSIGNOR TO HIMSELF AND BENJAMIN G. WELCH, OF DANVILLE, PENNSYLVANIA.

Letters Patent No. 105,568, dated July 19, 1870.

IMPROVEMENT IN BOLT-THREADING MACHINE.

The Schedule referred to in these Letters Patent and making part of the same.

To all whom it may concern:

Be it known that I, MAHLON HAMLIN, of Catawissa, in the county of Columbia, and in the State of Pennsylvania, have invented certain new and useful Improvements in Heads for Bolt-Cutters; and do hereby declare that the following is a full, clear, and exact description thereof, reference being had to the accompanying drawing and to the letters of reference marked thereon, making part of this specification.

The nature of my invention consists in the construction and arrangement of a head for bolt-cutters, as will be hereinafter fully set forth.

In order to enable others skilled in the art to which my invention appertains to make and use the same, I will now proceed to describe its construction and operation, referring to the annexed drawing, in which—

Figure 1 is a front view of the head, part of the face-plate being removed, and

Figure 2 is a horizontal section of the same.

A represents the head of the bolt-cutter, having in its front end three slots at equal distances apart, and radiating from the center. In these slots or mortises the dies B B are placed. The outer ends of the dies B B are beveled, as shown in the drawing, and at a suitable point on their under side is a slot, in which is inserted the outer end of a spring, C, which is secured in a recess on the head A.

The object of the springs C C is to throw the dies outward after the bolt has been cut.

A sleeve, D, is placed around the head A, and moves longitudinally on the same to force the dies inward, or close them so as to cut the bolt.

In the front end of the sleeve D is a circular recess, in which is placed a compensating ring, E. This ring is immediately around the head A, and provided on its inner circumference with three bevels, as shown in fig. 1, said bevels corresponding with the dies. The ring E moves with the sleeve D longitudinally on the head A, and the beveled ends of the dies, coming in contact with the inner surface of the ring, causes the dies to close.

It has also a revolving motion around the head and within the sleeve, and is operated in the following manner:

One or more screws, I, are inserted in the outside of the ring, and said screws pass through slots in the sleeve, so that the ring can be moved at will from the outside without disturbing either the head or the sleeve. The object of this motion is to compensate for the wear and tear of the dies.

Supposing the deepest parts of the bevels on the inside surface of the ring E are one inch, and then gradually lessening till they reach the inside surface of the ring, and the ring is set so that the dies are operated at this deepest portion of the bevels. Then, when the dies are worn out, so that they must be re-cut, they, of course, lose a certain portion in size; this is made up by turning the ring E far enough to make the dies move inward the same distance as before; hence I call this ring a "compensating ring."

By the proper adjustment of this compensating ring the bolts may also be cut so as to fit the nuts loose or tight, as may be desired, and for this purpose the slot or slots in the sleeve D, through which the screws I pass, may be graduated.

The front of the head A is covered by a face-plate, G, which confines the dies in their proper places.

Having thus fully described my invention,

What I claim as new, and desire to secure by Letters Patent, is—

The combination and arrangement of the head A, dies B B, springs C C, sleeve D, compensating ring E, and face-plate G, all constructed as described, and operating substantially in the manner and for the purposes herein set forth.

In testimony that I claim the foregoing, I have hereunto set my hand this 3d day of February, 1870.

MAHLON HAMLIN.
